(57) **CLAIM**

The ornamental design for a tail light set, as shown and described.

DESCRIPTION

FIG. 1 is a front right perspective view of a tail light set showing the first tail light of embodiment 1 according to the present invention;

FIG. 2 is a front left perspective view thereof;

FIG. 3 is a front view thereof;

FIG. 4 is a right side view thereof;

FIG. 5 is another front view thereof, showing the first tail light of embodiment 1 in a condition of use;

FIG. 6 is a front view of embodiment 1, showing both the first and second tail light, which is a mirror image of the first tail light, in a condition of use;

FIG. 7 is a front right perspective view of a tail light set showing the first tail light of embodiment 2, according to the present invention;

FIG. 8 is a front left perspective view thereof;

FIG. 9 is a rear right perspective view thereof;

FIG. 10 is a front view thereof;

FIG. 11 is a right side view thereof;

FIG. 12 is a top view thereof;

FIG. 13 another front view thereof, showing the first tail light of embodiment 2 in a condition of use; and,

FIG. 14 is a front view of embodiment 2, showing both the first and second tail light, which is a mirror image of the first tail light, in a condition of use.

The claim is directed to the collective appearance of the articles shown within each embodiment.

The broken lines define the bounds of the claimed design and form no part of the claimed design. De-emphasized and half tone portions of the taillight seen in FIGS. 1-4 and 7-12 illustrate portions of the article. The car shown in De-emphasized and half tone in FIGS. 5, 6, 13 and 14 illustrate environmental structure; all De-emphasized and half tone illustrations form no part of the claimed design.
